US00D954104S

(12) **United States Design Patent** (10) **Patent No.:** **US D954,104 S**
(45) **Date of Patent:** **** Jun. 7, 2022**

(54) **DISPLAY PANEL OR PORTION THEREOF
WITH A GRAPHICAL USER INTERFACE**

(71) Applicant: **MAGIC LEAP, INC.**, Plantation, FL (US)

(72) Inventors: **Tim Zurmoehle**, Fort Lauderdale, FL (US); **Andrea Isabel Montoya**, Plantation, FL (US); **Marshal Ainsworth Fontaine**, St. Augustine, FL (US); **Lorena Pazmino**, Wilton Manors, FL (US); **Alfred Yu-Chih Tarng**, Plantation, FL (US); **Genevieve Mak**, Fort Lauderdale, FL (US)

(73) Assignee: **Magic Leap, Inc.**, Plantation, FL (US)

(**) Term: **15 Years**

(21) Appl. No.: **29/726,148**

(22) Filed: **Feb. 28, 2020**

Related U.S. Application Data

(60) Division of application No. 29/658,942, filed on Aug. 3, 2018, now abandoned, which is a continuation of application No. 29/657,659, filed on Jul. 24, 2018.

(57) **CLAIM**

The ornamental design for a display panel or portion thereof with a graphical user interface, as shown and described.

DESCRIPTION

The sole FIGURE is a front view of a display panel or portion thereof with a graphical user interface showing our design.

The broken line showing of the display panel or portion thereof forms no part of the claimed design.

1 Claim, 1 Drawing Sheet
